ALBERT R. JONES, OF KANSAS CITY, MISSOURI.

ELECTRICAL PLUG CONNECTER.

Application filed June 8, 1925. Serial No. 35,656.

This invention relates to an electrical plug connector for connecting a contact to an electrical conductor wires that the wire can be plugged into a socket.

5 The primary object of the invention is to prevent slipping or disengagement of the end of the wire from the contact in the plug, and the invention consists in certain novel parts, all of which will be specifically referred to hereinafter, reference being had to the accompanying drawings, in which

10 Fig. 1 is a perspective view of the rear end of a lamp, and the plug connected attached to a wire but detached from the lamp 15 socket.

15 Fig. 2 is a disassociated perspective view of the plug shell, the contact member, the wire clamp ball, the pin for preventing longitudinal movement of the contact member, 20 and the end of the wire.

Fig. 3 is a longitudinal sectional view through the plug connector with the wire detached.

25 Fig. 4 is a similar view of the wire in clamping position.

Fig. 5 is a cross sectional view through the plug connector adjacent to the contact securing pin.

30 Fig. 6 is a cross sectional view through the plug connector showing the ball out of wire clamping position, and

Fig. 7 is a like view showing the ball in wire clamping position.

35 The lamp 1 may be of usual construction with a socket 2 to receive the shell 3 of a plug connector. The shell 3 externally may be of usual construction in that it may consist of a cylindrical shell with oppositely disposed pins 4 and 5 to be received in the 40 slots 6 and 7 in the usual way for securing the plugs to the sockets of lamps. The shell 3 may consist of insulating material such as hard rubber or the like. It is shown as having a longitudinal bore 8 to receive an elongated contact pin 9 with a longitudinal recess 10 therein, the wall of which is provided with an opening 11 through which a ball 12 may be introduced. The opening 11 coincides with a cam-shaped recess 13, that is, the wall of the recess is eccentric to the wall of the bore so that the ball can recede into the deepest portion of the recess to per-

mit the end 14 of an electrical conductor such as the wire 15 to be introduced into the recess between the wall of the recess and the ball 12.

When the contact pin 9 is turned so that the ball rides on the cam-shaped surface 14, the ball will be forced into the bore to clamp the end 14 of the wire securely against the wall of the bore in the pin 9. Since the pin or member 9 is of material having good conductivity, the current will flow from the wire into the contact so that the current may be supplied to the bulb 16 in the socket 2 of the lamp 1. The pin or member 9 is held against longitudinal movement by a pin 17 which is driven into the opening 18 in the shell of the plug. One end of the pin 17 is received in the annular groove 19 in the pin 9. In the annular groove is a stop wall 20 against which the pin 17 may contact. When one end of the wall 20 is against the pin, the opening 11 will be in register with the recess 13 so that the ball may be received in the deepest portion of the recess 13 to permit the wire to be introduced into the bore. For example, if the end of a screw-driver is inserted in the slot 21 in the end of the pin 9, and the pin is turned contra clockwise 80 and the web or stop 20 contacts with the pin 17 as shown in Fig. 5, the ball 12 may recede into the recess 13 and the end 14 of the wire may be pushed up into the recess 10 between the wall of the recess and the ball 12, as shown in Fig. 4. Now if the pin 9 is turned in a clockwise direction the ball 12 will ride on the wall of the recess 13 and clamp the wire against the wall of the recess 10 as shown in Fig. 4, so that the wire cannot be withdrawn, the camming action of the wall of the recess 13 being sufficient to jam the movable wire-securing member or ball against the wire to hold it in the recess 10; then when the plug 3 is inserted in the socket in the lamp, the end 22 of the pin 9 will contact with the end of the lamp bulb 16 to supply current to the filament thereof in the usual way.

85 It will be apparent that the parts of the plug can be easily constructed and conveniently assembled, and that danger of the wire becoming disconnected from the contact pin 9 will be entirely eliminated, be-

cause when the ball is forced against the cam surface of the recess 13 it will be imbedded into the wire and the wire will have sufficient spring to hold the ball against slipping.

Since the ball will make a depression in the wire as shown in Fig. 4, the wire cannot be easily pulled out of the plug. I prefer to use a spherical engaging member such as 10 the ball 12, but I am aware that other types of movable members may be employed, so I do not wish to be limited exclusively to the use of a sphere for maintaining intimate contact between the wire and the pin.

13. What we claim and desire to secure by Letters-Patent is:

1. A plug for electrical connectors, comprising a shell of insulating material provided with a central bore having a cam-shaped recess communicating with the bore, a longitudinally recessed contact member in the shell, the longitudinally recessed portion of the contact member having an opening in its wall to coincide with the cam-shaped recess, a ball in the opening having a part in the cam-shaped recess and a part in the recess in the contact member, the wall of

the cam-shaped recess being effective to force the ball into the recess in the contact to impinge the ball against a conductor wire receivable in the recess in the contact member, the contact member having an annular groove provided with a stop web across it and a pin passing through the shell received in the groove to contact with the stop member. 30 35

2. In a plug for electrical connectors, an insulating shell having a radial channel, a contact member rotatably disposed in said shell and having a bore for the reception of a conductor wire, means for wedging the wire in the contact member upon rotation of the contact member, the contact member having an annular groove and a stop wall limiting said groove, a pin in said radial channel of the shell projecting into said groove and adapted to retain the contact member in the shell and to limit the rotation of the contact member. 40 45

In testimony whereof we affix our signatures.

ARTHUR J. FROGUE.
JAMES I. SLOAN.
